(57) **CLAIM**

The ornamental design for a toy, as shown and described.

DESCRIPTION

FIG. 1 is a top left perspective view of a toy showing the claimed design;

FIG. 2 is a left front perspective view thereof; and,

FIG. 3 is a top front perspective view thereof.

The broken lines in the figures show portions of the toy and environment that form no part of the claimed design.

1 Claim, 3 Drawing Sheets

FIG. 1

FIG. 2

FIG. 3
